UNITED STATES PATENT OFFICE.

JOHN C. KISTLER, OF CLINTON, MISSOURI.

TIRE-SAVING JACK.

1,207,179.

Specification of Letters Patent. Patented Dec. 5, 1916.

Application filed February 17, 1916. Serial No. 78,938.

To all whom it may concern:

Be it known that I, JOHN C. KISTLER, a citizen of the United States, residing at Clinton, in the county of Henry and State 5 of Missouri, have invented certain new and useful Improvements in Tire-Saving Jacks; and I do declare the following to be a full, clear, and exact description of the invention, such as will enable others skilled in the art 10 to which it appertains to make and use the same.

This invention relates to certain new and useful improvements in tire saving jacks.

The primary object of the invention is to 15 provide a hoisting jack for sustaining the weight of a vehicle while standing in storage or in a garage, thus relieving the weight thereof from the pneumatic tires of the vehicle.

20 Another object of the invention is to provide a jack of this character, the raising means of which include an operating lever which is journaled to the base in order to allow it to be operated from substantially 25 any position relative to the side of the vehicle.

Another object of the invention is to provide a device of this character which will be of simple, strong and economical construction, and one which will be efficient and reliable in operation and well adapted to 30 the purpose for which it is designed.

With these and other objects in view, the invention consists of certain novel features 35 of construction and the combination and arrangement of parts as will be hereinafter fully described and claimed.

In the accompanying drawings forming a part of the specifications, and in which 40 similar reference characters designate like parts throughout the several views—Figure 1 is a side elevation of a device constructed in accordance with this invention; Fig. 2 is a central vertical longitudinal sectional view 45 of the same; Fig. 3 is a vertical sectional view taken on the plane of the line 3—3 of Fig. 2; Fig. 4 is a horizontal sectional view taken on the plane of the line 4—4 of Fig. 2; and Fig. 5 is a similar view taken on the 50 plane of the line 5—5 of Fig. 2.

The preferred form of the present invention comprises a base 1, an upright standard 2, and means for revolvably mounting the standard to the base. This base 1 is here 55 shown as being of rectangular configuration and provided on its upper side with a suit-

able circular recess 3. Extending upwardly from the opposite ends of the base 1 is a pair of converging flat metallic braces 4, the lower ends of which are provided with laterally extending feet 5 which are secured by suitable bolts or screws 6 to said base. The upper ends of the braces 4 are integrally united by a portion 8, and secured in any suitable manner, here shown by means 65 of rivets 7, to the portion 8 is a circular horizontal collar 9, the latter being arranged in vertical alinement with the recess 3 and being made from a flat strip of sheet metal, as shown.

The standard 2 of this improved jack is made from a single piece of metal, and is substantially U-shaped in cross section. Extending from the upper and lower ends of the standard 2 are tubular extensions 10 and 11 respectively, the upper extension 10 being journaled in the aforesaid collar 9, while the lower extension 11 is received and similarly journaled in the aforesaid recess 3 in the base 1. Thus it will be readily understood that the standard 2 is revolvably mounted with respect to the base 1.

Pivoted at 12 in the lower end of the standard 2 and between the sides thereof is a tubular link 13, the upper end of which 85 is provided with a pair of spaced pivot ears 14 between which is disposed and pivotally connected the intermediate portion of an operating lever 15. Slidably mounted in the upper extension 10 of the standard 2 is a 90 tubular lifting plunger 16, the lower end of which is bifurcated and pivoted to the extreme inner end of the lever 15. The lever 15 is offset laterally at a point spaced from the pivoted inner end thereof as is clearly 95 shown in the drawings, the free end thereof extending in substantially parallel relation to said pivoted inner end to provide a suitable handle by which it is operated. This tubular lifting plunger 16 is internally 100 threaded for the reception of an externally threaded shank 17 which depends from the lower side of a substantially rectangular flat metal supporting plate 18. Secured to the upper side of this plate 18 in any suitable manner, is a rubber or other suitable cushion 19, upon which the hub of the vehicle is adapted to rest. By this arrangement, it may be readily seen that vertical adjustment of the metal plate may be readily 110 and easily accomplished.

The device is particularly designed to be

used as a lifting jack for relieving the weight of an automobile or other vehicle from the tires thereof. When applying the device to use, the outer end of the lever 15 is raised and the rectangular metal plate 18 is adjusted to substantially the height of the hub of the automobile from the ground. By a downward thrust upon the outer end of the lever, the plunger 16 is raised and the 10 upper end of the link 13 is moved inwardly between the sides of the standard 2. It will be thus seen that when in this position, the link 13 and the inner arm of the lever 15 are arranged in substantially longitudinal and vertical alignment with the lifting plunger 16, and as the pivot connecting the upper end of the link 13 and the intermediate portion of the lever 15 is passed a trifle beyond dead center, the jack will be locked 20 in its raised position.

In the event that the garage is very narrow and there would not be room in which to swing the operating lever 15 to its upward position, provided, however, that the 25 same were extending laterally of the vehicle, the standard 2 may be easily and conveniently revolved in the recess 3 and collar 9, thereby allowing the lever to extend in a direction substantially longitudinally of the vehicle. This, as will be readily understood, is a very convenient feature of the invention.

From the foregoing description, taken in connection with the accompanying drawings, the operation and advantages of the 30 invention will be readily understood without a more extended explanation.

As various changes in form and propor-

tion and the minor details of construction may be resorted to without departing from the spirit of this invention, I do not wish 40 to be limited to the construction herein shown and described other than that set forth in the appended claim.

I claim:

A device of the class described comprising a base having a circular recess in the upper side thereof, a circular collar of flat sheet metal arranged horizontally above said base and in vertical alignment with said recess, 50 a pair of upwardly converging flat metal braces having means for attachment at their lower ends to said base at the ends thereof, said braces being integrally united at their upper ends and being firmly secured to one side of said collar, an upright standard made from a single piece of sheet metal and being substantially U-shaped in cross section and having tubular extensions at the 55 upper and lower ends thereof, the extension at the lower end of said standard being disposed and journaled in the recess in said base, the extension at the upper end of said standard extending through and being journaled in said collar, a lifting plunger slideable in the last referred to extension, and jack means for raising and lowering said plunger.

In testimony whereof I have hereunto set my hand in presence of two subscribing witnesses.

JOHN C. KISTLER.
